UNITED STATES PATENT OFFICE.

EDWARD A. FRANK AND HOWARD B. CURTIS, OF SENECA FALLS, NEW YORK.

DESIGN FOR AN EMBLEM, BADGE, PIN, FOB, RING, OR LIKE ARTICLE.

56,965.

Specification for Design.

Patented Jan. 25, 1921.

Application filed July 28, 1920. Serial No. 399,628. Term of patent 14 years.

To all whom it may concern:

Be it known that we, EDWARD A. FRANK and HOWARD B. CURTIS, citizens of the United States, residing at Seneca Falls, in the county of Seneca and State of New York, have invented a new, original, and ornamental Design for an Emblem, Badge, Pin, Fob, Ring, or like Article, of which the following is a specification, reference being had to the accompanying drawing forming

part thereof, in which the figure is a plan view of an emblem, badge, pin, fob, ring, or like article, showing our new design.

We claim:

The ornamental design for an emblem, badge, pin, fob, ring, or like article, as shown.

EDWARD A. FRANK.
HOWARD B. CURTIS.
